UNITED STATES PATENT OFFICE.

WILLIAM A. LORENZ, OF WEST HARTFORD, CONNECTICUT, ASSIGNOR TO THE OTAKA FABRIC COMPANY, OF HARTFORD, CONNECTICUT.

PAPER-CRINKLING APPARATUS.

Application filed July 18, 1927. Serial No. 208,255.

This invention relates to an apparatus for crinkling a web of paper or the like and has as its object to provide an apparatus of this sort having various features of novelty and 5 advantage.

More particularly an aim of the invention is to provide certain improvements in the paper crinkling machine illustrated in my Patent No. 1,548,790 issued August 4, 1925.

10 One of said improvements consists in providing pressure means for insuring proper stripping of the web from either or both of the cylinders at the desired points.

Other objects will be in part obvious and 15 in part pointed out more in detail herein-after.

The invention accordingly consists in the features of construction, combination of elements and arrangement of parts which will 20 be exemplified in the construction herein-after set forth and the scope of the application of which will be indicated in the appended claims.

In the accompanying drawings wherein I 25 have shown two embodiments which the present invention may take:

Figure 1 is a plan view showing my improved arrangement, this view being taken substantially on line 1—1 of Fig. 2;

30 Fig. 2 is a vertical sectional view taken substantially through the center of the apparatus and on the line 2—2 of Fig. 1;

Fig. 3 is an enlarged detail view of adjacent portions of the vacuum cylinders;

35 Fig. 4 is a view similar to Fig. 1, this view being taken substantially on line 4—4 of Fig. 5; and

Fig. 5 is a vertical sectional view taken substantially on line 5—5 of Fig. 4.

40 Referring to the embodiment illustrated in Figs. 1 to 3, A designates a cylinder which is adapted to carry a web to a receiving cylinder B. These cylinders are closely adjacent and just out of contact. The

45 receiving cylinder B has a slower peripheral speed than has the delivery cylinder A, so that as the paper is delivered from one cylinder to the other it is crinkled. In this embodiment the cylinders rotate in opposite 50 directions. The cylinder A is provided with a multiplicity of perforations 10 and the cylinder B is likewise provided with a plurality of perforations 11. The cylinders are geared together so as to rotate at the desired 55 relative speeds. In the present instance the

stub shaft 12 to which the cylinder A is fixed carries a gear 13 which meshes with a larger gear 14 carried by a stub shaft 15 to which the cylinder B is fixed. Obviously change gears may be interposed to vary the 60 relative speeds of the cylinders at will, depending on the extent of crinkle desired. The web of paper or pulp designated by the numeral 20 may come from a suitable supply roll or from a paper making machine, neither of which are shown as they form no 65 part of the present invention. The web passes between the cylinder 10 and a pressure roller 21. This roller presses the paper against the cylinder 10. If it is desired to 70 produce transversely crinkled paper which is longitudinally corrugated, the cylinders may be circumferentially corrugated as illustrated in Figs. 1 to 3. The circumferential ribs 22 of the cylinder A match with the 75 grooves 23 of the cylinder B. Also in this case the roller 21 may be circumferentially corrugated and mesh with the corrugations of the cylinder A as illustrated. The roller 21 may be connected up to the cylinder A 80 through gears 25. Also the circumferential ribs of the cylinder B may be of a wavy formation, thus providing these ribs with ruffles 26 and clearances 27 between the ruffles. The cylinder B carries the cross 85 crinkled and longitudinally corrugated paper to a receiving belt 28.

In accordance with the present invention, there is provided, preferably in each cylinder, a vacuum device for holding the paper 90 against the peripheries of these cylinders and also pressure means for stripping the paper from the cylinders at the desired points. Within the cylinder A is a hollow 95 stationary core 30 upon which the cylinder A closely fits. This core is open for a portion of its length and particularly between the roller 21 and the point of transfer from the cylinder A to the cylinder B in order that when suction is set up within the core, air may be drawn through the perforations 10 with the result that the atmospheric pressure will hold the web against the periphery of the cylinder A up to approximately the transfer point from the cylinder A to the cylinder B. The core 30 has a hollow hub 31 connected to a vacuum pipe 32 in order that air may be exhausted from the main chamber of the core. The core 30 is further provided with a pressure chamber 33 which 100 105 110

is open at its outer end, that is, at the inner periphery of the cylinder A. The mouth of this chamber is adjacent to and preferably is slightly to the delivery side of the point 5 of transfer from the cylinder A to the cylinder B. The pressure chamber 33 is connected by a pipe 34 to a suitable pressure device, not shown.

The cylinder B is provided with a core 10 36 which is generally similar to the core 30. The suction chamber of the core 36 is connected by a pipe 37 to a suction device, and the pressure chamber 38 is connected by a pipe 39 to a pressure device. The suction or 15 vacuum chamber of the core 36 is cut away from substantially the point at which the paper is delivered to the cylinder to the point at which it is discharged from the cylinder. The pressure chamber 38 has its mouth disposed adjacent the receiving belt 28. The 20 core 36 blanks the cylinder through the remaining portion of its periphery. The operation of the apparatus shown in Figs. 1 to 3 is briefly as follows: The web of paper 20 25 is delivered from a suitable source of supply and either in dry or moist condition, depending upon the requirements, between the roller 21 and the cylinder A where it is caused to take the corrugated form of the cylinder A. 30 Between the roller 21 and the cylinder B the web is caused to adhere to the periphery of the cylinder A by the suction created within the main chamber of the core 30. When the 35 web is transferred from one cylinder to the other it is transversely crinkled, owing to the fact that the cylinder B rotates at a slower peripheral speed than the cylinder A. Also due to the ruffles 26, the crinkling operation is expedited and the desired design 40 may be given to the web. After the paper has come into contact with the cylinder B, it is stripped from the cylinder A in order to insure its proper transfer by the combined action of the pressure within the pressure 45 chamber 33 and the suction within the core 36. The transversely crinkled and longitudinally corrugated paper is caused to adhere to the cylinder B between the cylinder A and the delivery belt by the suction within the 50 core 36, and when the paper comes opposite the belt 28 it is stripped from the cylinder B by the pressure within the pressure chamber 38, this pressure of course being effective through the perforations 11.

55 Referring now to the embodiment shown in Figs. 4 and 5, the cylinders A' and B' are generally similar to the cylinders A and B of the preceding embodiment, but they are not circumferentially corrugated, 60 the cylinder A' having a plain surface and the cylinder B having a ruffled surface, the ruffles being designated by the numeral 40. Also in this embodiment, the cylinder B' rotates in the same direction as the cylinder 65 A' and at a slower speed than the cylinder

A'. The web of paper 20 passes about suitable rollers 41 and onto the periphery of the cylinder A' against which it may be pressed by a roller 42. The cylinder A' is provided with a stationary core 43 the chamber 70 of which is connected up by a pipe 44 to a suitable suction device. The core blanks that portion of the cylinder with which a web is not in engagement. The cylinder B' is provided with a core 45 which is similar 75 to the core 36 of the preceding embodiment. The core 45 has a pressure chamber 46 which is connected up by a pipe 47 to a pressure device. 28 designates a receiving belt.

In the embodiment shown in Figs. 4 and 5 the web is carried by the rotating cylinder A' to the cylinder B'. Owing to the fact that the cylinder A' operates at a slower speed and has ruffles, the paper is transversely crinkled on this cylinder. The suction within the core 43, and effective through the perforations 10', causes the paper to adhere to the cylinder A' and the suction within the core 45 causes the paper to adhere to the periphery of the cylinder B' between the point where this cylinder receives the paper and the pressure chamber 46. The pressure within the chamber 46 is effective through the perforations 11' 90 in the cylinder B' to strip the paper from this cylinder.

95 As many changes could be made in the above construction and many apparently widely different embodiments of this invention could be made without departing from the scope thereof, it is intended that all matter contained in the above description or shown in the accompanying drawing shall be interpreted as illustrative and 100 not in a limiting sense.

105 It is also to be understood that the language used in the following claims is intended to cover all of the generic and specific features of the invention herein described and all statements of the scope of the invention which, as a matter of language, might be said to fall therebetween.

I claim as my invention:

110 1. In a paper crinkling apparatus, a cylinder, a second cylinder adjacent thereto adapted to receive a web therefrom and rotating at a slower speed than said first cylinder, one at least of said cylinders being 115 hollow and having perforations throughout its periphery, means whereby air may be exhausted from said cylinder to cause the web to adhere to the periphery thereof, and means whereby air may be blown through the perforations of said cylinder to strip the web therefrom.

120 2. In a paper crinkling apparatus, a cylinder, a second cylinder adjacent thereto and adapted to receive a web from and rotating at a slower speed than said first cyl- 125

- inder, one at least of said cylinders being hollow and having perforations throughout its periphery, a suction chamber within said hollow cylinder and effective through a portion of the periphery thereof for causing the web to adhere to the periphery of said cylinder, said hollow cylinder also having a pressure chamber adjacent the delivery point of said cylinder whereby air is blown through the perforations at that point to strip the web from said hollow cylinder.
3. In a paper crinkling apparatus, a cylinder, a second cylinder adapted to receive paper from said first cylinder and rotating at a slower speed than said first cylinder, one at least of said cylinders being hollow and having perforations throughout its periphery, and a core within said hollow cylinder having a suction chamber open to the periphery of said hollow cylinder, said core having a pressure chamber open to the periphery of said hollow cylinder adjacent the delivery point of the latter.
4. In a paper crinkling apparatus, a pair of adjacent hollow perforated cylinders adapted to deliver a web one from the other, the receiving cylinder rotating at a slower speed than the delivery one, means within each cylinder for exhausting air through the perforations thereof to cause the web to adhere to said cylinders, and pressure means within at least one of said cylinders for assisting in stripping the web from that cylinder at the delivery point thereof.
5. In a paper crinkling apparatus, a hollow cylinder having perforations throughout its periphery, a second cylinder rotating at a slower speed than and adapted to receive a web from said first cylinder, and means within said first cylinder for causing the web to adhere to the periphery thereof up to the point of transfer from one cylinder to the other, said first cylinder also having a pressure chamber adjacent the transfer point for assisting in stripping the web from the first cylinder and transferring it onto the second cylinder.
6. In a paper crinkling apparatus, a pair of adjacent hollow perforated cylinders adapted to deliver a web one from the other, the receiving cylinder being rotated at a slower speed than the delivery one, each of said cylinders having means therein for exhausting air through said perforations, each of said cylinders also having a pressure chamber adjacent its delivery point for assisting in stripping the web from the cylinder.

WILLIAM A. LORENZ.
